UNITED STATES PATENT OFFICE.

GEORGE RICHARDSON, OF LAMPASAS SPRINGS, TEXAS, ASSIGNOR OF ONE-HALF TO E. M. LONGCOPE, S. DUNCAN, AND J. S. LETCHER, ALL OF SAME PLACE.

SHEARING-MACHINE.

SPECIFICATION forming part of Letters Patent No. 415,125, dated November 12, 1889.

Application filed February 15, 1889. Serial No. 299,963. (No model.)

To all whom it may concern:

Be it known that I, GEORGE RICHARDSON, a citizen of the United States, and a resident of Lampasas Springs, in the county of Lampasas and State of Texas, have invented certain new and useful Improvements in Shearing or Clipping Machines; and I do hereby declare that the following is a full, clear, and exact description of the invention, which will enable others skilled in the art to which it appertains to make and use the same, reference being had to the accompanying drawings, which form a part of this specification, and in which—

15 Figure 1 is a perspective view showing my improved shearer in operation. Fig. 2 is a perspective view of the shearer alone. Fig. 3 is a longitudinal sectional view of the shearer and the flexible shaft. Fig. 4 is a top 20 plan view of the shearer with the top or upper parts of the handle and casing removed. Fig. 5 is a transverse section on the plane indicated by the line $x x$ of Fig. 3. Figs. 6, 25 7, and 8 are detail views, respectively, of the stationary and movable plates or cutter-plates and the wrinkle-guard. Fig. 9 is a view in section of the under side of the forward end of the machine, showing the springs for holding the wrinkle-guard; and Fig. 10 is 30 a cross-sectional view through the pressure-spring.

Like letters of reference denote like parts throughout the several views.

My invention relates to shearing or clipping machines; and it consists in certain improvements upon Letters Patent granted to me under date of June 12, 1888, No. 384,545, and more particularly in providing said device with what I designate an improved 40 "wrinkle-guard," and also in various other changes or improvements, as hereinafter more fully pointed out and described.

Referring to the several parts by letter, A indicates the lower or main part of the hand-grasp, B the top plate thereof, C the lower stationary cutting-plate, and D the upper movable cutting-plate, these parts being constructed and operated in a similar manner, as shown and described in my former patent, 45 hereinbefore referred to, except that the num-

ber of teeth upon the lower cutting-plate is preferably reduced to twelve, (in my former patent fourteen teeth being shown and described,) whereas in the upper movable plate I have increased the number of teeth to ten. 55

Suitably secured beneath the lower stationary plate C is a wrinkle-guard or plate E, said guard being of a width less than the width of the stationary plate, and provided with a series of upwardly-curved teeth F, 60 preferably eleven in number, which extend to within one-eighth of an inch of the ends of the teeth of the stationary plate, each tooth of the guard fitting exactly between the teeth of the stationary cutter-plate. The advantage of constructing this guard of a width less than the width of the stationary plate, and the teeth not extending forward as far as the teeth of said stationary plate is apparent, inasmuch as if the points of both sets of teeth 65 were exactly even they would not enter the wool so readily as when one set is shorter than the other. The wool once entering between the teeth of the stationary cutter becomes confined, and renders it much easier 70 for the teeth of the wrinkle-guard to enter. It will also be seen that as the teeth of the wrinkle-guard extend flush with the upper edge of the stationary plate in the center of the space between each tooth the free oscillating or reciprocating motion of the movable plate is not prevented.

I have shown this wrinkle-guard secured in place by two small springs G G, attached to the forward end of the hand-grasp, which 85 clamp it at H H and hold it firmly against the stationary cutter. It is obvious, however, that this guard may be secured in place by any other desirable means.

The upper cutting-plate D is provided on 90 its upper side with a small spring I, which acts as a pressure-spring, being fastened by a screw J, that extends through the lower stationary plate and screws into the center of the spring. The end of the spring presses on 95 the upper plate, in which there is a slot K, to allow said plate sufficient room to oscillate freely. By the employment of this pressure-spring the cutting of the wool or hair is much more easily accomplished, as it makes it an 100

impossibility for the plate to spring the least apart.

The stem L of the upper plate D has secured integral therewith a lever M. The rear end of the lever is formed with the two arms N N, which extend laterally and then rearwardly, as fully explained in my former Letters Patent. The extreme rear end of the lever M is provided with a slot O, a longitudinal perforation P intersecting it at right angles and passing through the laterally-extending arm of said lever. A screw Q passes through this longitudinal perforation, and is provided with threaded ends for the reception of locking-nuts R R, by which means any wear in either the eccentric-wheel A' or said arms can be readily compensated by tightening the nuts.

The letter T indicates the flexible shaft. In the drawings I have shown this shaft composed of a series of rods U, of iron, brass, or steel, as desired, and being preferably about one-fourth of an inch in diameter, said rods being provided with screw-threaded ends for the reception of sockets V. It is obvious, however, that any other construction of shaft may be employed, so long as the same possesses the quality of flexibility. The outer ends of the sockets have securely fastened therein a double coil of steel wire W, making the shaft extremely flexible, yet simple and durable.

The lower end of the flexible shaft terminates in a socket or coupling similar to those described for connecting the alternately-arranged series of rods and double coil steel wire, and rigidly secured in the end thereof, and extending into the casing, is a short shaft X, upon which the eccentric-wheel turns. It is obvious, however, that instead of the flexible shaft terminating in one of these couplings it may be provided on its end with a socket similar to that shown and described by me in Letters Patent No. 384,545. Upon the shaft X, between this lower coupling and the rear casing, I also prefer to provide a small balance-wheel Y, adapted to counteract the vibration caused by the eccentric-wheel while in rapid motion. The mechanism for turning and operating this shaft is substantially similar to that described in my former Letters Patent, No. 384,545, and need not therefore be specifically described.

It will be seen that this device differs in several important essentials from the invention as exemplified by Letters Patent hereinbe-

fore referred to. In the first place, I have provided an improved wrinkle-guard for the purpose of entirely preventing all wrinkles from getting between the teeth and being cut during the operation of shearing. By means of this simple device I can shear any sheep, be it ever so wrinkled, without the least fear of cutting it. The device will therefore be found particularly advantageous in shearing the American and Spanish merino sheep, in which grade the wrinkles are very common, and without this guard it is impossible to make a sheep-shearing machine do the work without injuring to a great degree. It will also be found desirable in adapting the device to the class of sheep mentioned to construct the same of a width of from four to three inches, which renders its utility much more effective.

I have also provided a simple and expeditious means for compensating for the wear caused by friction between the eccentricities and the rearwardly-extending portions of the pivoted lever, whereby said wear may be rapidly rectified.

Having thus fully described my invention, what I claim as new, and desire to secure protection in by Letters Patent of the United States, is—

1. A wrinkle-guard for clipping-machines, consisting of a metallic plate having a series of upwardly-curved teeth, said plate adapted to be secured beneath the lower cutter of the machine, and each tooth thereof fitting exactly between the teeth of said lower cutter, substantially as set forth. 85

2. The combination, with the handle having a casing at its rear end, of the stationary plate having a series of teeth, the movable plate provided with a series of teeth, the central pivoted lever having a slotted rear end and laterally and rearwardly extending arms, said laterally-extending portions being provided with a longitudinal perforation, the tightening-screw, the shaft mounted in the end casing, the eccentric disk mounted upon said shaft, and suitable means for revolving said shaft, substantially as set forth. 95 100

In testimony that I claim the foregoing as my own I have hereunto affixed my signature in presence of two witnesses.

GEORGE RICHARDSON.
